HEEL-SEAT FITTING MACHINE

Lloyd G. Miller, Beverly, Mass., assignor to
United Shoe Machinery Corporation, Borough
of Flemington, N. J.

Application October 25, 1939, Serial No. 301,247

11 Claims. (Cl. 12—31.5)

This invention relates to machines for fitting the heel-seat portions of attached soles of shoes for the reception of heels.

Preparatory to trimming the heel-seat portions of attached outsoles of shoes or sandals having open backs, for the reception of heels, by the use of a machine of the general type disclosed in United States Letters Patent No. 2,099,698, granted November 23, 1937, on an application filed in the name of Ralph S. Megathlin, for example, it is desirable to centralize the shoe in the machine by utilizing the rear part of the insole of the shoe.

The illustrative machine, as in the case of the machine disclosed in said Letters Patent, comprises a crease plate having a U-shaped opening, means including a bulger for forcing the central part of the heel-seat portion of the attached outsole of a shoe through said U-shaped opening and beyond one side of the plate, and a knife movable in a predetermined path along said one side of the plate to reduce the heel-seat portion of the sole. In order effectively to centralize shoes having open backs, there is provided, in accordance with a feature of this invention, a gage which is normally arranged in approximate engagement with said one side of the crease plate and in the path of movement of the heel-seat-reducing knife and which is of suitable shape to be engaged by and to centralize the rear portion of the insole of the shoe thereby centralizing the heel-seat portion of the outsole upon the crease plate, said gage being movable away from the path of movement of the knife so as to permit the knife to be moved in said path.

The various features of the invention will be understood and appreciated from the following description read in connection with the accompanying drawings, in which

40 Fig. 1 is a perspective view, partly in section and partly broken away, of a portion of an illustrative heel-seat fitting machine embodying the invention;

45 Fig. 2 is a perspective view, partly broken away, of a portion of a centralizing gage for locating a shoe widthwise in the machine.

50 Figs. 3, 4 and 5 are sections on line III—III of Fig. 1 during three successive stages of the heel-seat fitting operation; and

55 Fig. 6 is a perspective view of the heel end of a shoe which has had the heel-seat portion of its outsole fitted by the above machine, a heel which is later attached to the shoe being shown in dash lines.

The illustrative machine is described with reference to reducing the heel-seat portion 18 (Figs. 3, 4 and 5) of an attached outsole 20 of a shoe or sandal 22, which is mounted upon a last 24 and has an open back or rear end, for the reception of a heel 26 (Fig. 6), and comprises a crease plate 28 having a U-shaped opening 30 (Fig. 1), a back gage 32 and fingers 34 constituting a V-shaped centralizing gage, for positioning the heel-seat portion 18 of the outsole of the shoe lengthwise and widthwise, respectively, upon the crease plate, a clamp 36 (Figs. 3, 4 and 5) for forcing the margin of the heel-seat portion of the outsole against the upper side or face 38 (Figs. 1 and 5) of the crease plate, a bulger 40 (Figs. 3, 4 and 5) for forcing the central part of the heel-seat portion of the outsole through the U-shaped opening 30 and below a lower flat side or face 42 of the crease plate, vertically movable knives 44 for forming heel-breast receiving shoulders 45 (Fig. 6) upon the outsole of the shoe, and a knife 46 movable along the lower face 42 of the crease plate for reducing the heel-seat portion of the outsole and cooperating with the shoulder-forming knives 44 to form a heel-seat tab 47. The centralizing fingers 34 are pivotally mounted upon a side 48 which, if desirable, may be used to centralize shoes having complete counter portions, such shoes being hereafter referred to as "regular work."

The illustrative machine, with the exception of the centralizing fingers 34 and the forward portion of the slide 48 which supports the fingers, is practically identical with the machine disclosed in said United States Letters Patent No. 2,099,698 which, together with United States Letters Patent No. 2,053,295, granted September 8, 1936, on an application filed in the name of Fred L. MacKenzie, should be referred to for a complete understanding of the construction and operation of the machine.

It will be appreciated that the shoe 22 which has an open back cannot be effectively centralized by faces 50 of the slide 48 which, when the machine is operating upon regular work, are engaged by the rear counter portion of the shoe. Accordingly, the slide 48 is provided with bores 52 (Figs. 1 and 2) for receiving trunnions 54, respectively, of the centralizing fingers 34 which are normally urged upward against or in approximate engagement with the lower side 42 of the crease plate 28 by springs 56 (Figs. 2 and 3) which fit in pockets 58 of the slide 48 and engage the lower faces of the fingers. The work-

engaging faces 68 of the fingers 34 are arranged considerable distances ahead of the work-engaging faces 50 of the slide 48 so as to insure that when the machine equipped with the centralizing fingers 34 is operating upon regular work, as it is adapted to do, the work-engaging faces 50 of the slide shall not be contacted by the shoe counter.

The slide 48 is normally urged forward along 10 guideways 62 (Fig. 1) of the machine frame 63 by a pair of springs 64 until it engages an up-standing flange 66 of a stop slide 68 which is mounted for movement along a guideway 70 of the machine frame. Pivoted for movement 15 through a small arc on a pin 72 carried by the stop slide 68 is a block 74 to which a depending rod 76 is secured. Forward movement of the stop slide 68 under pressure of the slide 48 is limited by the engagement of the rod 76 with 20 the frame 63 of the machine.

The back gage 32 is movable along a vertical guideway 78 of a carrier slide 80 which is supported by the machine frame and is movable along a guideway 82 (Fig. 1) at the under side 25 of the stop slide 68. Secured to the back gage 32 is a pin 84 (Figs. 3, 4 and 5) which is normally held in engagement with a shoulder 85 (Fig. 5) of the carrier slide 80 by a spring 86, the lower end of which embraces the pin 84 and the upper 30 end of which is fastened to the carrier slide 80. It will be noted that when the machine is idle the upper face 88 (Fig. 1) of the back gage 32 is approximately in alinement with the lower face 42 of the crease plate 28.

35 The carrier slide 80 is provided with a slot 90 through which the block 74 passes, and is constantly urged forward with relation to the stop slide 68 by a spring 92, forward movement of the carrier slide 80 with relation to the stop 40 slide 68 being limited by the engagement of a flange 93 of the carrier slide with the rear end of the stop slide.

The shoe is placed in the machine with the heel-seat portion 18 of its attached outsole 20 45 overlying the crease plate 28 and its insole 94 in engagement with the centralizing fingers 34. The operator then forces the shoe and therefore the fingers 34 carried by the slide 48 rearwardly until the rear end of the insole 94 engages the 50 back gage 32, the fingers during such movement centralizing the shoe. As the operator continues to move the shoe rearward the carrier slide 80 engages the upstanding flange 66 of the stop slide 68 which is moved rearward under pressure 55 of the shoe until the block 74 pivoted to the stop slide engages a spiral face 96 of a cam 98.

The cam 98 is operatively connected to a movable abutment of a gage (not shown) constructed and arranged to measure lengthwise the heel to 60 be attached to the shoe, and may be swung into different operative positions in accordance with the length of the heel measured in the gage. The construction and arrangement of the heel gage and the shoe-positioning mechanism are such 65 that when the heel-seat portion 18 of the attached outsole 20 of the shoe or sandal has been trimmed, the heel, which has been measured in the gage and is correctly positioned upon the shoe, will have its breast in snug engagement 70 with the heel-breast receiving shoulders 45 formed upon the outsole.

After the shoe has been positioned in the machine the operator depresses a treadle (not shown) causing the clamp 36 to force the margin 75 of the heel-seat portion 18 of the outsole 20 posi-

tioned upon the crease plate 28 against the face 38 of the plate, as shown in Fig. 3. When the treadle is further depressed a one-revolution clutch (not shown) is tripped causing the bulger 40 to force the central part of the heel-seat portion 5 of the outsole 20 through the U-shaped opening 30 and below the lower face 42 of the plate 28, as shown in Fig. 4, and simultaneously therewith causing the shoulder-forming knives 44 to be moved to their lowered positions past the 10 forward edges 99 (Fig. 1) of the crease plate 28 to form the heel-breast receiving shoulders 45.

During the above movement the back gage 32 and the centralizing fingers 34 maintain their operative positions in the plane of the lower face 42 15 of the crease plate 28, as illustrated in Fig. 4, the heel end of the shoe upper being depressed slightly by the bulger 40. As the machine continues to operate, the heel-seat reducing knife 46 moves forward with its cutting edge 100 in engagement 20 with or approximately in engagement with the lower face 42 of the crease plate 28 to reduce the heel-seat portion 18 of the sole and to cooperate with the knives 44 to form the heel-seat tab 47.

During the forward travel of the heel-seat- 25 reducing knife 46 the back gage 32 is forced downward along the guideway 78 of the carrier slide 80, and the centralizing fingers 34 are swung downward about the common axis of the trunnions 54 away from the crease plate 28 and out 30 of the path of travel of the heel-seat-reducing knife 46 to their positions shown in Fig. 5. With the above arrangement it will be clear that the back gage 32 and the centralizing fingers 34, which, when the machine is idle and while the 35 shoe is being positioned in the machine are arranged in the plane of the lower face 42 of the crease plate, can be effectively engaged by the insoles 94 of shoes having open backs so as to locate the shoes accurately in the machine, and are movable away from the crease plate 28 so as to 40 enable the heel-seat-reducing knife 46 to move along the under face of the crease plate 28 to reduce the heel-seat portion 18 of the attached sole 20 of the shoe. 45

Having described the invention, what I claim as new and desire to secure by Letters Patent of the United States is:

1. In a heel-seat fitting machine, a crease plate having an opening, a gage for positioning the heel-seat portion of an attached outsole of a shoe widthwise upon one side of the plate, said gage being mounted for movement toward and away from the plate, and means for normally forcing said gage into approximate engagement with the other side of said plate. 50

2. In a heel-seat fitting machine, a crease plate having an opening, a gage for positioning the heel-seat portion of an attached outsole of a shoe widthwise upon one side of the plate, said gage being mounted for movement along and also toward and away from said plate, and means for normally forcing said gage against the other side of the plate. 60

3. In a heel-seat fitting machine, a crease plate having a U-shaped opening, a slide movable lengthwise of the U-shaped opening, a shoe centralizing gage pivoted to said slide, and resilient means interposed between the slide and the gage for forcing the gage with yielding pressure 65 against said plate.

4. In a heel-seat fitting machine, a crease plate having a U-shaped opening, a slide movable lengthwise of the U-shaped opening, means comprising a back gage for positioning the heel- 75

seat portion of an attached outsole of a shoe upon one side of the plate, said means comprising a pair of fingers which are mounted for movement upon the slide and are constructed and arranged to centralize the heel-seat portion of said outsole upon said one side of the plate, and a spring interposed between the slide and each of the fingers for normally forcing said fingers into approximate engagement with said plate.

5 5. In a heel-seat fitting machine, a crease plate having a U-shaped opening extending from one side of the plate to the other, a back gage for positioning the heel-seat portion of an attached outsole of a shoe lengthwise upon said one side of the plate, a centralizing gage mounted for rectilinear movement along said other side of the plate lengthwise of the U-shaped opening and also mounted for pivotal movement toward and away from said plate, and means for normally forcing the centralizing gage against said other side of the plate.

10 6. A heel-seat fitting machine having, in combination, a crease plate having an opening extending from one side of the plate to the other, centralizing and back gages arranged adjacent to said one face of the plate for positioning the heel-seat portion of an attached outsole of a shoe upon said other side of the plate, means 15 for forcing the central part of the heel-seat portion of the sole through said opening and beyond said one side of the plate, and a knife movable in a predetermined path along said one side of the plate to reduce the heel-seat portion of the sole, said centralizing and back gages being mounted for movement away from said one side of the plate in response to movement of the knife in said path.

20 7. A heel-seat fitting machine having, in combination, a crease plate having a U-shaped opening extending from a flat side of the plate to an opposite side of the plate, centralizing and back gages arranged approximately in the plane of said flat side of the plate for positioning the heel-seat portion of an attached outsole of a shoe upon said opposite side of the plate, means 25 for forcing the central part of the heel-seat portion of said outsole through the U-shaped opening and beyond said flat side of the plate, and means comprising a knife which is movable in a predetermined path along said flat side of the plate for reducing the heel-seat portion of the sole, said centralizing and back gages being constructed and arranged to be moved lengthwise of the U-shaped opening by the shoe and also to be moved away from said flat side of the plate by the knife as it moves in said path.

25 8. A heel-seat fitting machine having, in combination, a plate for supporting the heel-seat portion of an attached outsole of a shoe having an open back, said plate having a U-shaped opening, a V-shaped gage which is normally in engagement with the plate and is constructed and arranged to be engaged by the insole of the

30 shoe to position said heel-seat portion of the outsole of the shoe widthwise upon the plate, means for positioning the shoe lengthwise of the plate, and means for reducing the heel-seat portion of the outsole, said gage being movable lengthwise of the U-shaped opening along the plate and also toward and away from said plate.

35 9. A heel-seat fitting machine having, in combination, a crease plate for supporting the heel-seat portion of an attached outsole of a shoe, a gage for positioning the heel-seat portion of the outsole of the shoe lengthwise upon the plate, a pair of centralizing fingers for positioning said heel-seat portion of the outsole widthwise upon the plate, springs for urging the fingers to their operative positions against the crease plate, and a knife movable in a predetermined path and having its cutting edge approximately in engagement with said plate for reducing the heel-seat portion of the sole, said fingers being constructed 40 and arranged to be swung away from the crease plate in response to movement of the knife during its movement in said path.

45 10. A heel-seat fitting machine having, in combination, a crease plate having a U-shaped opening extending from one side of the plate to the other, a slide movable lengthwise of the U-shaped opening, a back gage movable lengthwise of the U-shaped opening for positioning the heel-seat portion of an attached outsole of a shoe lengthwise upon said one side of the plate, a pair of fingers pivoted upon the slide and constructed and arranged to centralize the heel-seat portion of the outsole upon said one side of the plate, springs for urging said fingers into approximate engagement with said other side of the plate, means for forcing the central part of the heel-seat portion of the outsole through the U-shaped opening and beyond said other side of the plate, and a knife movable in a predetermined 45 path along said other side of the plate for reducing the heel-seat portion of the outsole, said fingers being constructed and arranged to be swung with relation to the plate in response to movement of the knife to permit the knife to be moved in said path.

50 11. In a heel-seat fitting machine, a crease plate having an opening, a gage for positioning the heel-seat portion of an attached outsole of a shoe widthwise upon one side of the plate, means for forcing the central part of the heel-seat portion of the sole through the opening of the crease plate and beyond the other side of the plate, a knife movable in a predetermined path with its cutting edge in approximate engagement with said other side of the plate for reducing the heel-seat portion of the sole, and means for normally forcing said gage into approximate engagement with said other side of the plate and into the path of movement of the knife, said gage being movable out of the path of movement of the knife to permit said knife to be moved in said path.

LLOYD G. MILLER.
